SPIKE SHOE SOLE

Daniel J. McCarthy, Somerville, Mass., assignor to Converse Rubber Corporation, Malden, Mass.

Filed Oct. 9, 1970, Ser. No. 25,411

Term of patent 14 years

Int. Cl. D2—04

U.S. Cl. D2—321

FIG. 1

FIG. 2

FIG. 3

FIG. 4

FIG. 5

FIG. 1 is a bottom plan view of a spiked shoe sole showing my new design;

FIG. 2 is a top plan view thereof;

FIG. 3 is a side elevational view, the other side being substantially identical;

FIG. 4 is a front elevational view; and

FIG. 5 is a rear elevational view.

The characteristic feature of my design resides in the combination on a shoe sole of five pointed stars having at their centers outwardly extending spikes, all as shown on the drawing.

I claim:

The ornamental design for a spike shoe sole, as shown and described.
